UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

GUN-BARREL.

1,102,667.

Specification of Letters Patent.

Patented July 7, 1914.

Application filed February 2, 1914. Serial No. 815,989.

To all whom it may concern:

Be it known that I, THOMAS C. JOHNSON, a citizen of the United States, residing at New Haven, in the county of New Haven and State of Connecticut, have invented a new and useful Improvement in Gun-Barrels; and I do hereby declare the following, when taken in connection with the accompanying drawings and the characters of reference marked thereon, to be a full, clear, and exact description of the same, and which said drawings constitute part of this application, and represent, in—

Figure 1 a plan view of a gun-barrel constructed in accordance with my invention. Fig. 2 a view thereof in side elevation. Fig. 3 a broken plan view of the muzzle-end of the barrel, drawn to the full scale and showing by a broken circular line how the stock 20 of the sighting-rib may be removed to produce the struts which support it throughout its length. Fig. 4 a corresponding view in side elevation. Fig. 5 a view in transverse section on the line *a*—*b* of Fig. 4.

My invention relates to an improvement in that class of gun barrels provided with ventilated sighting-ribs; the object being to produce a gun barrel of the character described of superior strength, mechanical 30 structure and appearance.

With these ends in view, my invention consists in a gun-barrel having an integral ventilated sighting-rib supported by a continuous series of struts arranged in alignment under the axial center of the rib.

In carrying out my invention as herein shown, I form upon the top of the barrel 2, a sighting-rib 3 made integral therewith. This rib is ventilated to prevent the distortion of the barrel due to the repeated shooting of the gun in rapid succession, by means of wide, regularly spaced transverse ventilating-openings 4 uniform in shape and size and formed in the base of the rib below its upper surface which is continuous. The production of the said transverse openings 4 results in the formation of a series of regu-

larly spaced, squat struts 5 also uniform in shape and size and axially arranged in strict alinement with the central longitudinal axis 50 of the rib. In default of a better term, these struts may be characterized as diamond shaped. The said struts 5 may, and preferably will be, produced by means of a circular cutter represented in Fig. 3 of 55 the drawings by means of a broken semi-circle 6, this cutter being applied to the opposite sides of the initially solid rib which it penetrates, the cutter extending past the center thereof, whereby the said openings 4 60 and the said struts 5 are produced and the latter given their diamond shape with slightly concaved faces. As all of the struts 5 are arranged in exact alinement, the effect is not only symmetrical and mechanically 65 correct, but also of superior functional result, inasmuch as the rib is uniformly supported throughout its length against all downward or lateral blows, whereby the likelihood of its being distorted or displaced 70 is reduced to the minimum. Furthermore, the symmetrical arrangement of the struts 5, and hence their even distribution considered as masses of metal, reduces to the minimum their liability to distort the rib in case the 75 same becomes over-heated from the barrel as the result of firing the gun in rapid succession. The symmetrical arrangement of the struts under the rib also provides for its uniform ventilation and cooling. 80

I claim:—

A gun-barrel having a ventilated, integral sighting-rib supported throughout its length by a single symmetrically arranged series of diamond-shaped struts the long 85 axes of which are coincident with the central longitudinal axis of the rib.

In testimony whereof, I have signed this specification in the presence of two subscribing witnesses.

THOMAS C. JOHNSON.
